UNITED STATES PATENT OFFICE.

JOSEPH A. HICKEY, OF PHILADELPHIA, PENNSYLVANIA, ASSIGNOR OF ONE-HALF TO
FRANCIS BANCROFT, OF MERCHANTVILLE, NEW JERSEY.

MACHINE FOR MANUFACTURING ABRADING-DISKS.

1,291,513.

Specification of Letters Patent.

Patented Jan. 14, 1919.

Application filed August 26, 1916. Serial No. 116,975.

To all whom it may concern:

Be it known that I, JOSEPH A. HICKEY, a citizen of the United States, residing in the city and county of Philadelphia, State 5 of Pennsylvania, have invented certain new and useful Improvements in Machines for Manufacturing Abrading-Disks, of which the following is a specification.

One of the objects of my invention is to 10 provide a machine for the manufacture of disks, such as abrading disks, blocks, etc., from or out of plastic material in which said material is applied successively in relatively thin layers. In other words, only a 15 small portion of material is added to the disk or similar article at one time during its manufacture.

A further object of my invention is to 20 provide an apparatus by means of which disks of relatively great and uniform density may be produced.

A still further object of my invention is to provide a machine which is simple in construction and which may be manufactured 25 at relatively small cost and which at the same time is extremely practical and efficient in operation.

Other objects and advantages of my invention will be pointed out in the detailed 30 description thereof which follows or will be apparent from such description.

In the drawings:—

Figure 1 is a view in side elevation of a 35 machine embodying my invention;

Fig. 2 is a transverse, horizontal sectional view taken on the line 2—2 of Fig. 1;

Fig. 3 is a longitudinal sectional view of a portion of the machine shown in Fig. 1;

Fig. 4 is a similar view showing a slightly 40 modified construction of my invention;

Fig. 5 is a transverse sectional view of a portion of apparatus embodying my invention and showing a modification of the construction; and

Fig. 6 is a sectional plan view of a part 45 of the machine showing a modification of the construction.

Referring to the drawings, 1 designates the floor or foundation upon which the side 50 posts or standards 2 of the machine are supported. 3 designates a mold, cylindrical in the construction shown, provided with brackets 4 which terminate in sleeves 5 through which the side supporting posts or 55 standards 2 extend. The said sleeves are

secured in fixed positions upon the posts 2 by means of binding screws 6. 10 designates a revolute shaft which extends upwardly through a bearing 11 formed at the center of the cross-piece 12 provided at its opposite ends with sleeve-like portions 13 through which the side supporting posts or standards 2 extend. The member 12 may be adjusted to different positions upon the said posts or standards and secured in such positions by 60 means of binding screws or bolts 14.

16 designates a second cross-bar provided with a central sleeve-like bearing 17 through which the revolute shaft 10 extends, and also provided with bearings 18 adjacent to 70 its opposite ends through which the supporting side posts or standards 2 extend.

20 designates a collar secured to the shaft 10 immediately underneath the bearing portion 17 of the cross-piece 16 so that as the 75 shaft 10 is raised, as will be hereinafter described, the cross-piece 16 together with the parts connected therewith, will be correspondingly raised or lifted by reason of the contact of the collar 20 with the underneath 80 side of the bearing portion 17 of the cross-piece 16.

21 designates portions of the cross-piece 16 which project beyond the sleeve-like bearing portions 18 and from which weights 22 85 are supported by means of depending rods 23. The weights supported by each of these depending rods 23 consist of a plurality of members one or more of which may be removed so as to vary the weight supported 90 by the projecting end portions of the cross-piece 16.

25 designates a stationary cross-piece secured to the upper end portions of the side supports or standards 2. Said cross-piece 95 is provided with a bearing 26 in which the upper end portion of the revolute shaft 10 is supported and guided.

It will be understood that the cross-piece 12 may be adjusted to the desired position 100 with respect to the other parts of the structure and fastened permanently in such position upon the side supports or standards 2.

The shaft 10 is provided with a wheel 27 to which power is applied by means of a 105 band or otherwise for driving said shaft.

Secured to the lower end of the revolute shaft 10 is a device for forming the disk in the mold, the said device comprising a plurality of arms 30 (four in the construction 110

shown, although the number may be increased or diminished as may be desired) which extend radially outwardly. The edges of these arms may extend in straight lines, 5 as shown in Fig. 2 of the drawings, or the edges, particularly what may be termed the operative or forward edges, may be crooked as indicated at 31 in Fig. 6 of the drawing in which the operative edge is shown as 10 being angular, although if desired such operative edge may be curved instead of angular.

The operative or forward edge portions of these arms may be slightly rounded off as 15 indicated at 32 in Fig. 3 or the undercutting or beveling may be greatly increased as indicated at 33 in Fig. 4. I also prefer to construct the upper sides of the said arms with a sloping or inclined surface, such as 20 is shown at 34 in Fig. 3, or such as is shown at 35 in Fig. 4. In the former case the lower edge of the inclined surface terminates in line with the lower surface of the arms 30 whereas in the latter the inclined surface 35 25 terminates at 36 a considerable distance above the lower side arms.

Centrally of its lower end the revoluble shaft 10 is provided with a short cylindrical projection 40 around which the plastic material 41 is packed, as shown in Fig. 3, to 30 form the central opening 42 through the disk to provide means for attaching the disk to its holder or support in practical operation.

35 In order to insure that the plastic material shall be packed firmly around the projection 40 I prefer that the inner ends of the beveled or inclined portions 32 or 33 shall terminate in inwardly inclined surfaces as indicated at 43 in the drawings.

40 It is found, however, that such inclined surfaces are not actually necessary although it is preferred that they shall be present.

In Fig. 5 I have shown a construction in 45 which both edges of the arms are undercut as shown at 33 and 45 and in which also the upper side of the arm is wedge-shaped, that is to say, terminates in an acute angle as shown at 46.

50 The bottom of the mold is closed by means of a removable plate or disk 50 supported upon a head 51 upon the upper end of a plunger 52 operated in any suitable manner, as by means of a hydraulic press. By 55 dropping the head 51, the bottom 50 may be removed and the disk which has been formed in the mold also removed.

In the several constructions shown it is assumed that the shaft 10 rotates in a clockwise direction.

By constructing the operative edges of the arms 30 in the manner shown in Fig. 6 in which the inner and outer end portions are angularly related with respect to each 65 other the tendency is to cause the plastic

material to be compressed more uniformly from the center to the outer edges thereof, which, of course, is a very desirable feature as the more uniformly at all points the material of the disks is compacted the more 70 satisfactory will the operation of the said disks be.

If it should be desired to manufacture different sized disks, that is to say, disks of different diameters, this may be accomplished merely by inserting into the mold 3 a sleeve, such as 60. The thickness of these sleeves may be varied so that a single apparatus may be employed for manufacturing 75 disks of a considerable number of different 80 diameters. It would also be necessary to change the arms upon the lower end of the shaft 10 so as to have them of a length to fit snugly inside of the mold, as is shown in the several figures of the drawing. 85

In the employment of my apparatus in the manufacture of abrading disks or similar articles, the bottom 50 is placed in position as shown in Figs. 3 and 4 of the drawings with the shaft 10 in such position that 90 the arms 30 are situated near the said bottom. The plastic material is then poured into a mold upon the top of the arms. As the arms rotate in the direction already indicated the rounded or undercut forward 95 operative edges thereof cause small portions of the plastic material to be spread out and compacted first directly against the bottom 50 and thereafter in successive thin layers one upon the other until the disk is of the 100 thickness desired. As the thickness of the disk increases the shaft 10 is lifted carrying with it the driving wheel 27, the cross-piece 16, and the weights 22 supported thereon. The force exerted by the parts 105 thus lifted acts to compress and thoroughly compact the plastic material as the disk is formed. Such force may be increased or diminished by increasing or diminishing the weight of the weights 22. 110

It should be understood that the abrading disk forming device may consist of a single arm only, with its forward operative edge rounded off as shown in Fig. 3 or undercut in the manner shown in Fig. 4. In 115 such case the arm may be widened so that it becomes in fact a disk-like plate having a radial slot therein, one edge of which is rounded off or undercut as desired to effect the laying or spreading of the superposed 120 plastic material to form the abrading disk. By varying and increasing the amount and angle of the rounded off or undercut portion the thickness of the layers of plastic material applied in the construction of the 125 abrading disk may be varied. In consequence the density or compactness of the disk may be varied and controlled. When the disk is built up by the successive application of their layers it is more condensed 130

and more uniformly compacted than if it is built up by the application of thicker layers successively.

In actual practice it would be convenient 5 and desirable to have on hand a number of disk forming devices having different rounded off or undercut portions at their operative edges so that one device may be substituted for another as may be desired.

10 I claim:—

1. In a machine of the character described, the combination of a mold having a bottom, a revoluble shaft, one or more arms secured to and extending radially from the lower end of said shaft and rotating therewith, the outer end portion or portions of the forward or operative side or sides of said arm or arms being angularly related to the inner portion or portions thereof, the 15 said outer end portion or portions being bent or extended in the direction of the rotation thereof and the lower forward or operative edge or edges of the said arm or arms being rounded off or beveled and

means for causing revolution of the said 25 shaft.

2. In a machine of the character described, the combination of a mold having a bottom, a revoluble shaft, means for causing rotation of said shaft, one or more arms 30 secured to and extending radially from the lower end of said shaft and rotating therewith, the forward lower operative edge or edges of the said arm or arms being rounded off or beveled and the outer end portion 35 or portions of the said arm or arms being bent and extended in the direction of rotation thereof at an angle to the inner remaining portion or portions of said arm or arms, and means tending to cause relative 40 movement between the said mold and the said shaft in the direction of the axis of the latter.

In testimony that I claim the foregoing as my invention, I have hereunto signed my 45 name this 25th day of August, A. D. 1916.

JOSEPH A. HICKEY.
